O. M. KNOX

POLE

Filed Oct. 11, 1926

UNITED STATES PATENT OFFICE.

ORVILLE M. KNOX, OF KNOXBORO, NEW YORK, ASSIGNOR OF ONE-THIRD TO LINCOLN
G. ARCHER, OF KNOXBORO, NEW YORK.

POLE.

Application filed October 11, 1926. Serial No. 140,973.

This invention relates to improvements in poles, designed especially for supporting telephone, telegraph, lighting and other transmission lines, and has for its object to provide powerful indestructible poles of relatively light and cheap construction, that are formed of metal, preferably rolled steel or iron. A further object is to reinforce the poles by imposing upon the opposite faces 5 metal plates of novel design, which may also be produced in a simple and inexpensive manner by rolling. Each pole and its reinforcing members are especially designed for facilitating rapid, accurate and economical fabrication, and wherein the lower portion of the pole which is embedded in the earth is provided with internal and external ribs or vanes for solidly anchoring, as well as for preventing the accidental rotation of 10 the pole, when the latter is subjected to certain strains. A further object is to provide an all-metal pole of the class, which may take the place of, and afford greater strength and durability, than the short-life wooden 15 poles in common use, and which may, owing to the growing scarcity of suitable timber be produced at greatly reduced cost. And a further object is to provide poles of the class which are uniformly straight and which 20 when erected present neat and symmetrical appearance throughout the line.

The invention relates particularly to improvements in the poles shown and described in my United States Patent Numbered 35 1,270,625, dated June 25, 1918.

I attain these objects by the means set forth in the detailed description which follows, and as illustrated by the accompanying drawing, in which—

40 Figure 1 is an elevational view of the complete pole, to which my improvement is applied. Fig. 2 is a top-plan view of the same. Fig. 3 is an enlarged broken longitudinal section, taken on line 3—3 of Fig. 45 5. Fig. 4 is a horizontal section taken on line 4—4 of Fig. 3. Fig. 5 is a similar view, taken on line 5—5 of Fig. 3. Fig. 6 is an end view of the body of the main pole. And Fig. 7 is an end view of one of the reinforcing plates. 50

In the drawing, 2 represents the angular body of the pole, which is preferably L-shaped in cross-section. The body 2 is

preferably made of rolled steel or iron, and the leaves 2' thereof are preferably the same 55 breadth and thickness throughout the length of the pole. The opposite faces, particularly of the bottom portion of the body 2, are reinforced by similar T-shaped plates or members 3 and 4, the said plates preferably being rigidly secured to the body by rivets 5, which are driven through corresponding perforations in the body and plates, as shown in Figs. 3, 4 and 5. The members 3 are preferably about one-half the length 60 of the members 4, so as to effect the progressive reinforcement from the top towards the bottom of the pole, and the members 3 are independently mounted on the inner walls of the body 2, as best seen in Figs. 70 2, 3, 4 and 5. In practice the plates 3 are about one-quarter the length of the pole 2, and are provided especially for reinforcing the extreme lower portion of the body, corresponding parts of which are embedded in 75 the earth, as shown. The plates 3 are preferably formed with central longitudinal stems or ribs, which enable me to produce reinforcing plates of great strength by rolling, from relatively thin steel at comparatively low cost. By this construction and arrangement, there is little danger of either the pole or the plates buckling or warping 80 when the poles are subjected to wind and wire-stretching strains. The plates 4 are substantially like the plates 3 in cross-section, and are preferably the same breadth and thickness, so that they may be formed by the same rolling dies. The plates 4 preferably extend upwardly past the middle of 90 the body 2, and are mounted independently upon the outer walls of the flanges 2', as best seen in Figs. 1, 3 and 5. The ribs or stems 4' of the plates 4 face outwardly, and when these plates are securely fastened to the body 2 by the rivets 5—5', they not only supplement the reinforcement of the lower end of the body effected by the plates 3, but they 95 also tend to stiffen and reinforce the portion of the pole above the plates 3, thereby preventing undue flexing or breaking and distorting of the medial portion of the pole. The flanges 2', above the tops of plates 4 are usually punched to facilitate the mounting of several cross-arms, as 6 and 6', which support the wires (not shown), and said

100 105

arms may be either permanently riveted, or detachably bolted to the body 2, as desired.

Having thus described my invention, what I claim, is—

A pole composed of a body of substantially L-shape in cross section, and reinforcing plates secured to the inner and outer faces of each of the sides of the body, the 10 plates secured to the outer faces of the body being of greater length than the inner plates, all of said reinforcing plates having outwardly facing longitudinal ribs extending substantially throughout the length of the

plates and the ribs on the same side of the body being disaligned, the outer side edges of the bases of the outer reinforcing plates being spaced from the adjacent outer side edges of the sides of the body and the inner side edges of the bases of the outer reinforcing plates being spaced from the angle of the body, the ribs and all of said edges affording a multiplicity of individual ground engaging portions whereby rotation of the body is prevented.

In testimony whereof I affix my signature.

ORVILLE M. KNOX.
